[57] CLAIM

The ornamental design for the brush, as shown.

DESCRIPTION

FIG. 1 is a top plan view of a brush, showing my new design;

FIG. 2 is a side elevational view thereof;

FIG. 3 is a bottom plan view thereof, shown with the bristles removed for ease of illustrations;

FIG. 4 is an end elevational view of the brush as shown in FIG. 3;

FIG. 5 is a top perspective view thereof;

FIG. 6 is a top perspective view taken from the opposite end thereof.

FIG. 1

FIG. 2

FIG. 3

FIG. 4
